(57) **CLAIM**

The ornamental design for a shoe with rollerskate motif, as shown and described.

DESCRIPTION

FIG. 1 is an upper perspective view of a shoe with roller-skate motif, according to the new design;

FIG. 2 is a bottom perspective view of the shoe of FIG. 1;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines are included for the purpose of illustrating environmental structure and form no part of the claimed design.

1 Claim, 8 Drawing Sheets
